UNITED STATES PATENT OFFICE.

EDWARD A. FARR, OF MERIDEN, CONNECTICUT, ASSIGNOR TO FOSTER, MERRIAM & COMPANY, OF MERIDEN, CONNECTICUT, A CORPORATION OF CONNECTICUT.

DESIGN FOR A TEAKETTLE OR SIMILAR ARTICLE.

56,555.

Specification for Design.

Patented Nov. 9, 1920.

Application filed March 19, 1919. Serial No. 283,684. Term of patent 3½ years.

To all whom it may concern:

Be it known that I, EDWARD A. FARR, a citizen of the United States, residing at Meriden, county of New Haven, State of Connecticut, have invented a new, original, and ornamental Design for a Teakettle or Similar Article, of which the following is a specification, reference being had to the accompanying drawing, forming a part thereof, in which—

Fig. 2 is a side elevation corresponding with Fig. 1; and

Fig. 3 is an elevation as seen from the left in Figs. 1 and 2.

What I claim and desire to secure by Letters Patent is:—

The ornamental design for a teakettle or similar article, substantially as shown.

In testimony whereof I affix my signature.

EDWARD A. FARR.
